Baldwin Wright

UNITED STATES PATENT OFFICE.

JOSEPH BARTA, OF MARTINS FERRY, OHIO.

LAMP-HOLDER FOR MINERS' CAPS.

1,397,200.

Specification of Letters Patent.

Patented Nov. 15, 1921.

Application filed January 18, 1921. Serial No. 438,216.

To all whom it may concern:

Be it known that I, JOSEPH BARTA, a citizen of the United States, residing in Martins Ferry, in the county of Belmont and

5 State of Ohio, have invented certain new and useful Improvements in Lamp-Holders for Miners' Caps, of which the following is a specification.

10 This invention relates to devices of the kind employed for supporting lamps on miners' caps in order that the hands of the miner may be free to work, the lamps being so held as to afford the necessary illumination.

15 Heretofore such devices have not, so far as my knowledge extends, been so made as to hold the lamp with such security as to keep it from swinging laterally and back and forth when mounted on the cap, and 20 the object of this invention is to so construct the holder that these objections may be overcome.

25 In carrying out my invention, I provide a Z-shaped frame of such form that it may be readily secured to the cap and on the upper part of this frame I secure a metal plate provided with a tubular downwardly extending socket to receive the suspending hook of the lamp and which joins a flanged, 30 grooved portion which receives the hook and prevents it from swinging, the arrangement being such that while the lamp may be readily applied to, or taken from, the cap it is prevented from swinging or wabbling either laterally or back and forth when in use.

35 In the accompanying drawings:—

Figure 1 is a perspective view of a miner's cap with my improvements applied.

40 Fig. 2 is a sectional view of a portion of the cap and the lamp-holder and shows how the lamp is held on the cap.

45 Fig. 3 is a top plan view of the device adapted to be applied to the lamp-holding frame to prevent the lamp from turning or swinging in any direction.

Fig. 4 is a bottom plan view of this device, and

Fig. 5 is a front elevation thereof.

50 The drawings show a miner's cap A of well known construction to which is secured in the usual way a Z-shaped frame B. It may be riveted at b to the top of the cap and at b' to the vizor. The frame is so made as to stand out from the front of the

cap, as shown in Fig. 2, and it is slotted at b², as usual. As thus far described the device is of usual or well known construction.

55 Experience has demonstrated that in the use of this kind of holder the lamp will swing in various directions which is objectionable for many reasons. In order to prevent this, I attach to the top of the frame a metal plate C formed with a downwardly extending tubular socket c, the upper end of which is beveled at c³ and joins a groove c', extending from the top of the socket toward the front of the plate and bounded on each side and at the rear by a flange c². 70 The groove extends from the top of the socket nearly to the front of the plate where it joins a slotted part c⁴ registering with the slot b² of the frame.

75 The lamp D is provided with a hook d as usual and when suspended it is held in the manner shown in Fig. 2.

80 It will be observed that the straight end d' of the hook enters the socket c while the top or horizontal part of the hook lies in the groove c' between the flanges c². When thus mounted the lamp is so held that it cannot swing fore and aft and cannot turn from side to side. The socket prevents the fore and aft movement but a pivotal movement in the socket would not be prevented were it not for the flanges shown on opposite sides of the groove.

85 I claim as my invention:

90 A device for supporting a miner's lamp upon a cap comprising the usual frame slotted at its upper end, and a plate rigidly attached thereto and formed with a tubular downwardly extending socket passing through one end of the slot in the frame 95 and closely engaging the vertical part of the hook of the lamp, said plate having on its upper face a groove extending forwardly from the upper part of the socket and raised flanges at the sides of said groove 100 spaced to engage closely the side of the hook, whereby lateral and swinging movement of the lamp is prevented, the upper face of said plate at the sides and rear of the groove being beveled to guide the lamp 105 hook while being inserted.

110 In testimony whereof, I have hereunto subscribed my name.

JOSEPH BARTA.
